United States Patent Office.

JACOB STEFFE, OF PHILADELPHIA, ASSIGNOR TO ORR, PAINTER & CO.,
OF READING, PENNSYLVANIA.

Design No. 4,823, dated April 18, 1871.

DESIGN FOR A COOKING-STOVE.

The Schedule referred to in these Letters Patent and making part of the same.

I, JACOB STEFFE, of the city of Philadelphia and State of Pennsylvania, have invented and produced a new and original Design for Cook-Stoves, of which the following is a specification.

The nature of the design is fully represented in the accompanying photographic illustrations, to which reference is made.

Figure 1 is a perspective view of the stove A.

Figure 2 is a face view of the back plate B.

On the fire-plate C, above the fire-doors D D, is the title of the stove "Advance."

The title is also placed on the side plates E, above the oven-doors D'.

The name of the manufacturing firm, "ORR, PAINTER & CO.", is on the raised panel F of the said side plate C, below the oven-doors D'.

The fire-doors D have a central elliptical ornament, a, surrounded by a bead, b, from which projects divergent ornaments d, the outer extremities of which give a rectangular form to the ornamentation corresponding to the form of the door.

The small side doors D" have a like ornamentation to that of the fire-doors D.

The oven-doors D' have an elliptical central ornament, a', surrounded by a wreath, e, from which project corner divergent ornaments d'.

The contour of the ornamentation corresponds to the shape of the door, the wreath e spreading toward the sides and ends of the door, filling up the spaces between the corner ornaments d', and making a finish with the same.

The back plate B, seen in fig. 2, of the stove has a middle raised panel, H, and side panels H' H'.

The panel H is of rectangular form, and the side panels H' H' rounded at their ends.

The panel H has a carved ornament, I, and the panels H' H', ornaments I' I' in their general appearance much like the ornament I.

I claim as my invention—

The design for cook-stove, as shown and described.

In testimony whereof I have hereunto set my hand and affixed my seal this 16th day of March, 1871.

J. STEFFE. [L. S.]
